(57) CLAIM

The ornamental design for a golf club hosel piece, as shown and described.

DESCRIPTION

FIG. 1 is a bottom perspective view of the golf club hosel piece of the present invention;

FIG. 2 is a front side view thereof;

FIG. 3 is a rear side view thereof;

FIG. 4 is a left side view thereof;

FIG. 5 is a right side view thereof;

FIG. 6 is a bottom plan view thereof;

FIG. 7 is a top plan view thereof; and,

FIG. 8 is a top perspective view thereof.

The broken lines are included for the purpose of illustration only and form no part of the claimed design.
